YARN PRODUCTION

William E. Neff, Richmond, Va., assignor to E. I. du Pont de Nemours & Company, Wilmington, Del., a corporation of Delaware

Application December 20, 1941, Serial No. 423,749

2 Claims. (Cl. 28—71.5)

This invention relates to the production of yarn composed of artificial filaments. More especially, it relates to a method of and apparatus for automatically winding an advancing yarn in a number of helical courses about a plurality of coacting yarn-advancing rollers, at least one of which is positively driven. The method and apparatus is especially useful in "stringing up" a plurality of spaced, cantilever type, yarn-advancing rollers such as a feed wheel arrangement in a wet spinning process, i.e., a process in which yarn is spun by extruding a filament-forming solution through a spinneret into a coagulating bath and the yarn is continuously removed by means of a feed wheel arrangement to a collecting device.

The spinning of rayon by the bucket spinning process involves, among other things, the step of passing the freshly formed yarn about a positively driven feed wheel of known peripheral speed, whereby the yarn speed is controlled and the final denier of the yarn determined. It is, of course, important that slippage of the yarn about this wheel be prevented and, as the art has resorted to increased spinning tensions and to higher spinning speeds, it has been necessary to pass the yarn about the feed wheel in a plurality of helical courses to secure the necessary degree of contact and prevent slippage of the yarn at this point. To maintain the helical yarn courses separate from each other and prevent abrasion of the yarn, the art has generally resorted to a feed wheel arrangement wherein a separate rotatable roller (usually thread driven) is mounted, in spaced relation, adjacent the positively driven feed wheel, and in which the feed wheel and spaced roller are, or one of them is, frusto-conical in shape, or in which the axes of the two rollers are either canted or askew to each other. Thus, helical courses of yarn passing about the rollers will be displaced from one another and advanced along the rollers as the latter rotate. Inasmuch as cooperating frusto-conical rollers and canted or askew cylindrical rollers operate in substantially the same way, the present invention will be described with particular reference to frusto-conical rollers having substantially parallel axes.

It has been customary, heretofore, when starting up a spinning position, to pass the freshly formed yarn about the rollers of the feed wheel arrangement by hand, the yarn passing from the feed wheel roller, or the spaced roller, being introduced into the collecting means, for example, the spinning bucket in a bucket spinning process, with the aid of a stream of liquid under conditions of free fall. Although this process is time-consuming and requires considerable dexterity on the part of the operator, it has proved satisfactory for use with yarn spinning speeds of the

order of 3600 inches per minute. However, it is not suitable for use with the greatly increased yarn spinning speeds of the order of 10,000 inches per minute that the art is now demanding. This is primarily because of the difficulty of moving the hand rapidly enough and in the exact, required manner to wind the rapidly advancing yarn a sufficient number of times about the feed wheel roller and displacement roller to provide sufficient contact to prevent slippage. As a second point, it is found that the yarn, once it is wrapped about the roller of the feed wheel arrangement, cannot be directed into the collecting means by the action of a freely falling stream of water because water under conditions of free fall does not move fast enough in its initial stages to aid in directing the rapidly advancing yarn.

It has been proposed in the past to drive the roller of the feed wheel arrangement at a low peripheral speed of the order of 3,000 inches per minute during the "stringing up" operation, and then increase the speed to the desired amount when the yarn was following the desired path. The initially wound yarn was not of the correct denier, of course, and had to be removed from the fully wound yarn cake and discarded as waste. Furthermore, unless the rotation speed of the feed wheel was increased very slowly, the advancing yarn was quite likely to break.

A similar proposal involved the use of a feed wheel arrangement wherein the feed wheel proper was formed with two cylindrical portions of different diameter, the two portions being connected by a central conical portion. In operation, the yarn was first passed about the smaller cylindrical portion and then, when the "stringing-up" operation was completed, the yarn was transferred to the larger diameter portion which possessed the final desired peripheral speed. This process was also open to the same objection as the above one. Moreover, certain spinning techniques, such as those involving the use of a rapidly flowing coagulating bath, and which have been designed for use with high spinning speeds, are not applicable to use with low spinning speeds. Thus, these methods of "stringing-up" a feed wheel arrangement, involving the use of an initial low spinning speed cannot be used with certain desirable spinning set-ups designed particularly for high speed spinning.

Automatically operated means of passing a yarn about a yarn-advancing means comprising two or more non-parallel rollers have been proposed in U. S. Patent No. 2,136,556 to Lovett and U. S. Patent No. 2,165,259 to Helm. Both of these means, however, require a complicated mechanism and are generally objectionable for that reason. Furthermore, these means are not primarily concerned with the passing of a yarn

about rollers at a high speed, nor do they make any provision for finally separating the free end of the advancing yarn from the feed wheel and directing it downwardly to the collecting means.

It has also been proposed to wind first a long auxiliary length of yarn or other strand-like material about the feed wheel arrangement in the desired manner at a time when the rollers comprising it are not rotating. The forward end of the freshly spun, advancing yarn can then be joined on to the trailing end of this auxiliary yarn and the feed wheels set in operation, whereby the advancing yarn will be passed about the rotating rollers in the desired manner. However, this method is time-consuming and objectionable in that the auxiliary yarn must be wound about the rollers of the feed wheel arrangement by hand. Moreover, it is very difficult to operate such an arrangement at high speeds since the yarn-advancing rollers must be set in operation at the exact moment the advancing yarn is joined to the auxiliary yarn.

It is, therefore, an object of this invention to provide a simplified method of positioning a yarn, in a series of helical courses, about a plurality of spaced, cantilever yarn-advancing rollers.

It is a further object of this invention to provide a simple, automatically operated means to position a yarn in a series of helical courses about a plurality of spaced, cantilever yarn-advancing rollers.

It is another object of this invention to provide such a means that can be used to wind the yarn about the said yarn-advancing rollers at very high yarn speeds, of the order of 10,000 inches per minute.

Other objects of the invention will appear hereinafter.

The present invention will be more clearly understood by reference to the following detailed description when taken in connection with the accompanying illustrations, in which:

Figure 1 is a perspective view showing an apparatus constructed in accordance with the present invention.

Figures 2, 3, 4 and 5 are side elevational views showing the successive steps in a method of positioning a yarn in successive helical courses about the apparatus of Figure 1.

Figure 6 is a vertical sectional view of a fluid yarn-directing device.

Figure 7 is a sectional view taken along the line 1-1 of Figure 6.

Figures 8, 9, 10, 11 and 12 are side elevational views showing the successive steps in another method of positioning a yarn in successive helical courses about the apparatus of Figure 1.

Figures 13 and 14 are elevational views showing yarn wraps and belt removed from the apparatus of Figure 1 after the latter has been strung up.

Figure 15 is a side elevational view of a modified form of apparatus for use in accordance with the present invention.

Figure 16 is a front elevational view of Figure 11.

Figure 17 is a side elevational view of a modified form of apparatus constructed in accordance with the present invention.

Figure 18 is a front elevational view of still another modified form of apparatus suitable for use in accordance with this invention.

Referring to Figures 1 through 5 of the drawings, reference numerals 21 and 23 designate spaced frusto-conical rollers such as are commonly used in a feed wheel arrangement for pos-

itively forwarding a freshly coagulated yarn from a coagulating bath to a bucket in a bucket spinning process. The rollers 21 and 23 are cantilever type rollers supported at one end by the respective shafts 25 and 27.

At least one of the shafts is rotated in a positive manner to advance the yarn at a constant speed and, if desired, both shafts may be positively driven to rotate at equal peripheral speeds. In the latter case, it may be desirable to construct both rollers of identical size. Alternatively, one of the rollers may be driven by frictional contact of the yarn. A fixed, yarn guide rod 29 is positioned adjacent the shaft end of the rollers to guide the oncoming yarn 31 on to this end of the rollers. A belt 33 is positioned over the free ends of the rollers to rotate therewith.

Since the rolls are frusto-conical, the belt must be held on to the rollers. For this purpose an arm 35 is pivoted adjacent the free ends of rollers 21 and 23. The arm 35 is pivoted at 37 to a lug 39 fixed on support 41. A cross-bar 43 is fixed on arm 35. The cross-bar 43 is adapted to swing into contact with belt 33. A branch arm 36 is fastened at an angle to arm 35. A weight 45 is adjustably mounted on branch arm 36 whereby to cause a pressure of cross-bar 43, of the desired magnitude, on the belt 33. A latch means, such as hook 49 on the support 41 and a cooperating eye 47 on the weight may be provided for the purpose of fastening arm 35 and cross-bar 43 in an inoperative position.

The yarn 31 may be caused to position itself in helical courses about the rollers 21 and 23 in the manner shown in Figures 2 to 5 inclusive. Figure 2 shows the yarn being brought under guide 29 and over roller 21. This may be readily done by hand. The guide 29 is positioned at such an angle as to continuously guide the yarn on to the shaft end of the feed roller 21. The belt 33 is positioned over the free ends of rollers 21 and 23 to rotate therewith. The belt is held in position by means of cross-bar 43.

Figure 3 shows the yarn, after passing over the roller 21, being pulled over into contact with belt 33. The yarn may be passed under guide 29, then over roller 21 and diagonally across roller 21 into contact with belt 33 by hand in one continuous motion. The yarn, being wet, will readily cling to the belt and be caused to wind on to the rollers adjacent the belt.

Figure 4 shows the accumulation of a number of yarn windings in the form of a wrap 51 adjacent the belt. Due to the pull on the yarn by guide 29, these yarn windings of the wrap 51 will be drawn back along the rollers to spread themselves evenly in successive helices along the rollers as shown in Figure 5, with a new yarn wrap 51 building up adjacent the belt. When the yarn is travelling uniformly along the rollers one of the helical yarn courses adjacent the free end of the rollers is severed and passed to any desired type of collecting device (not shown). The yarn may, for example, be torn, or otherwise severed, by hand at the point 53, and then the advancing end of yarn forwarded to a collecting device such as a spinning bucket or the like. The belt 33 and the dead wrap 51 may now be removed at the convenience of the operator.

Figures 6 and 7 of the drawings illustrate a fluid impelling device, generally designated by 51, which is particularly adapted for use in passing the yarn 31 from the feed rollers 21 and 23 to a collecting device such as a rotating

bucket. This device 61 is particularly useful when the yarn is being spun at high speeds of the order of 6,000 to 12,000 inches per minute. The device 61 comprises a nozzle 63 positioned in a support 68 attached to a base plate 67. The nozzle 63 is supplied with a fluid, either liquid or gas, through conduit 64. A fine tube 65, adapted to emit a fine stream of fluid, is positioned at the mouth of the nozzle 63. The base plate 67 is provided with a V-shaped groove 69 in which the yarn 31 is positioned. The nozzle 63 and tube 65 are arranged at such an angle to the base plate 67 that the fine stream of fluid 71 is directed against the yarn passing through the bottom of the groove 69. This fine stream 71 has a high velocity due to pressure on the fluid and causes the yarn 31 to be rapidly forwarded in a downward direction.

Figures 8 to 12 and 16 show the progressive steps involved in another method of stringing yarn on to the feed rollers 21 and 23. Figure 8 shows the yarn 31 brought under guide 29 and over roller 21 where it is allowed to accumulate in a wrap 55 until the belt 33 is positioned over the free ends of the rollers 21 and 23. The belt may be held on by hand, or it may be held on by a cross-bar 43 as shown in Figure 1. The last yarn winding in wrap 55 is now torn or cut from the other windings in wrap 55 and is placed in contact with belt 33 to rotate therewith as shown in Figures 9 and 10. The yarn now winds on to the rollers 21 and 23 adjacent the belt to form a wrap 51 as in Figures 2 to 5. The dead wrap 55 is now moved, beneath the winding yarn, to the free end of roller 21 adjacent wrap 51. The pull of guide 29 again causes the yarn to position itself in successive helical courses about the rollers 21 and 23 as shown in Figure 11. One of the helical yarn courses 53 adjacent the wraps 55 and 51 is now caught in the V-shaped groove of a fluid yarn impelling device 61 (see Figures 11 and 16). The yarn is now severed approximately at the point 59 shown in Figure 16, and the yarn guided to the desired collecting device by the high velocity stream of fluid of the device 61, as shown in Figure 12.

Figures 13 and 14 show respectively the yarn wraps 55 and 51, and the belt 33 removed from the ends of the rollers 21 and 23 after the yarn is being forwarded in a continuous manner to the collecting device.

Referring to the modified form of yarn-advancing device shown in Figure 15, the yarn is advanced by canted cylindrical rollers 81 and 83. The yarn is positioned in successive helical courses on this type of yarn advancement apparatus in the same manner as in the modifications above described.

Figure 17 of the drawings illustrates a pair of frusto-conical yarn-advancing rollers 21a and 23a provided with grooves 85 and 87 respectively. These grooves are made with sufficient depth to maintain belt 33 therein. By this construction other means for holding the belt on to the rollers can be dispensed with.

Figure 18 of the drawings illustrates a yarn-advancing arrangement comprising four rollers 91, 93, 95 and 97 instead of the two rollers above-described. By the use of additional rollers, the yarn can be forwarded with a lesser

number of helical courses in view of the greater frictional contact.

In the above-described apparatus, the yarn-advancing rollers may be of any desired construction, it being only necessary that the yarn windings about both rollers be of gradually smaller length so as to advance the yarn in successive helical yarn courses. The invention pertains, of course, to a plurality of spaced 10 yarn-advancing rollers since the difficulties of stringing the yarn on the rollers do not appear in single or interleaved yarn-advancing rollers.

Obviously, any means for holding the belt on to the ends of the rollers can be used equally 15 well as the specific structures disclosed.

This invention provides a satisfactory method whereby an advancing yarn can be rapidly and automatically wound in a helical manner about a pair of rotating yarn-advancing rollers.

The invention also provides a means for directing a yarn to and depositing it on a conveyor belt, especially at high spinning speeds.

The means provided by this invention is eminently suited for use with very rapid yarn speeds, 20 of the order of 10,000 inches per minute or even higher. The invention makes the use of these high yarn speeds entirely feasible in connection with spinning equipment requiring the use of 25 pairs of yarn-advancing rollers about which the yarn must be passed in a series of helical courses.

The invention requires very little equipment 30 over and above that required by conventional processes employing yarn-advancing rollers. Moreover, the process of the invention is very 35 simply and rapidly conducted.

No claim is made in this application for the fluid impelling device per se described herein since this device is specifically claimed in Millhisser Serial No. 426,184, filed January 9, 1942.

Since it is obvious that many changes and 40 modifications can be made in the above-described details without departing from the nature and spirit of the invention, it is to be understood that the invention is not to be limited to the details 45 described herein except as set forth in the appended claims.

I claim:

1. The method of positioning a yarn in a series of helical courses about a plurality of spaced, 50 cantilever yarn-advancing rollers which comprises positioning a belt about the outwardly projecting ends of said rollers to rotate therewith, passing a yarn, and maintaining the passage of said yarn, on to the opposite end of one 55 of said rollers, drawing a portion of said yarn into contact with said belt to rotate therewith whereby upon continued rotation of said rollers the yarn will arrange itself in helical form about said rollers, severing the yarn adjacent the projecting ends of said rollers, guiding the same to a collecting means, and removing the belt together with accumulated yarn windings from said rollers.

2. A yarn-advancing mechanism comprising 65 a plurality of spaced, cantilever yarn-advancing rollers, a belt positioned about the outwardly projecting ends of said rollers, and means pivotally positioned adjacent the projecting ends of said rollers, said means adapted to swing against said belt to maintain the same on said rollers.

WILLIAM E. NEFF.
